US0D1105732S

(12) **United States Design Patent** (10) **Patent No.:** **US D1,105,732 S**
(45) **Date of Patent:** **** Dec. 16, 2025**

(54) **PARASOL**

(71) Applicant: **Glatz AG**, Frauenfeld (CH)

(72) Inventor: **Pablo Bernal Ruesta**, Stuttgart (DE)

(73) Assignee: **Glatz AG**, Frauenfeld (CH)

(**) Term: **15 Years**

(21) Appl. No.: **29/992,100**

(22) Filed: **Mar. 5, 2025**

Related U.S. Application Data

(63) Continuation of application No. 35/518,318, filed on Mar. 9, 2023 (U.S. filing date under 35 U.S.C. 384), and having an international filing date of Mar. 9, 2023, now abandoned.
